COMB CLEANER

James F. Hunter, Turtle Creek, Pa.

Application June 20, 1939, Serial No. 280,103

2 Claims. (Cl. 132—29)

This invention relates to new and useful improvements in comb cleaners, more particularly to a novel construction of a supporting frame for mounting a stranded cloth material whereby the latter is adjustable to vary the tension as desired.

Heretofore it has been proposed to utilize fabric strands stretched taut over a frame member through which the teeth of a comb are moved to cleanse the teeth, but such devices are either too cumbersome in size and weight or impractical in the mounting of the fabric strands thereon. Furthermore, as the strands stretch from use, there has been no satisfactory adjustment available for rendering them taut, which is an essential characteristic of a fabric strand comb cleaner.

In accordance with the present invention, I provide a light-weight frame structure having a handle portion thereon, and having a bridge at opposite ends across which the fabric strands are stretched, the stranded portion being detachably secured to the bridges in a manner to render them adjustable.

Another object of the invention is the provision of a textile structure consisting of a plurality of parallel strands terminating in regular knitted ends which are looped to receive anchorage pins that are adjustably mounted in the supporting frame structure, the frame having a plurality of engaging portions for the anchorage members whereby the strands may be rendered taut as desired.

The invention will become more apparent in consideration of the accompanying drawing constituting a part hereof in which like reference characters designate like parts and in which:

Fig. 1 is a view in perspective of a frame or base member provided with a gripping handle on which to mount the textile strands or fabric for cleaning the comb;

Fig. 2 a view in perspective of the stranded material with woven ends in the form of loops which are shown flattened out in the drawing;

Fig. 3 a side elevational view of the supporting frame and fabric member;

Fig. 4 a top plan view thereof showing the anchorage members partially disposed in the slotted openings of the frame.

In the drawing, the numeral 1 generally designates a stretching frame having end bridges 2 and 3, the latter being provided with a handle portion 4. The frame structure is of two or three inches in width to accommodate a woven textile strand unit generally designated by the numeral 5, Fig. 2. The frame portion is of such cross-

section in the wall of the base as to render it somewhat flexible when produced of wood or resinous molding compositions, so that tension can be maintained on the strands of the member 5 when stretched across the bridges 2 and 3. For mounting the stranded element, the bridges 2 and 3 are provided with cylindrical openings 6, 7, 8 and 9, having vertical slots 10, 11, 12 and 13. The fabric unit 5 is constructed with its ends of knitted material looped around in the form of a tube with center openings 14 and 15 adapted to receive mounting pins or rods 16 and 17, Fig. 4. By inserting the fabric ends in the slots 10 and 12 in register with either pairs of openings 6 and 8 or 11 and 13, the rods or pins 16 and 17 can be inserted in the fabric openings 14 and 15, thus securely mounting the strand unit 5 on the frame member 1 with the strands taut, as shown in Figs. 3 and 4.

If through use or because of exposure to moisture or otherwise the strands 5 stretch, one of the anchor rods can be removed and the loose end of the unit 5 can be lowered to the next opening 1 or 9 and the rod again inserted, thus stretching the strands across the bridges 2 and 3 of the supporting frame.

In the use of the device, the teeth of the comb are inserted between the stretched strands 5 and the comb is drawn back and forth with the strands rubbing the edges of the teeth to remove any lint or other foreign substances from the teeth.

The hereinbefore described comb cleaner is especially adapted for use with renewable strand elements 5 which because of their inexpensive construction can be frequently renewed for sanitary reasons.

In mounting the strand units on the frame, the frame can be stood on end and pressed downward to flex the back 1 of the frame so that after adjustment, when pressure on the frame is released, it will right itself to its normal position, and produce tension on the strands 5 to maintain them in a taut position.

Although one embodiment of the invention has been herein illustrated and described, it will be evident to those skilled in the art that various modifications may be made in the details of construction without departing from the principles herein set forth.

I claim:

1. A comb cleaner comprising a supporting frame having a pair of spaced bridges and a handle, cylindrical openings extending through said bridges having vertical slots communicating

therewith, and a plurality of fabric strands having end portions for receiving anchorage pins disposed across said bridges, and being secured in the openings thereof by a plurality of pins extending therethrough.

5. A comb cleaner comprising a supporting frame having a pair of spaced bridges for mount-

ing the ends of fabric strands, said bridges having slotted openings for receiving the looped ends of the strands, and anchorage pins adapted to be inserted through the loops of the strands and the openings of the bridges to thereby maintain 5 the strands taut across the bridges of the frame.

JAMES F. HUNTER.
